CLAIM

The ornamental design for an adjustable squirrel baffle, as shown and described.

DESCRIPTION

FIG. 1 is a perspective view of an adjustable squirrel baffle showing my new design;

FIG. 2 is a bottom, rear and left side perspective view thereof;

FIG. 3 is a bottom perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view showing the adjustable squirrel baffle with its upper part open;

FIG. 11 is an enlarged view of portion 11 in FIG. 1;

FIG. 12 is an enlarged view of portion 12 in FIG. 1;

FIG. 13 is an enlarged view of portion 13 in FIG. 3;

FIG. 14 is an enlarged view of portion 14 in FIG. 4;

FIG. 15 is an enlarged view of portion 15 in FIG. 10;

FIG. 16 is a perspective view showing the adjustable squirrel baffle in an assembled state; and,

FIG. 17 is a perspective view showing the adjustable squirrel baffle in an alternate assembled state.

The evenly dashed broken lines illustrate features of the adjustable squirrel baffle that form no part of the claimed design. The broken lines showing an environmental structure in FIG. 16 and FIG. 17 are for illustrative purposes only and forms no part of the claimed design. The unevenly dashed broken lines define the boundary of enlarged views and form no part of the claimed design.
